UNITED STATES PATENT OFFICE.

WILLIAM T. BOOTH, OF EAST ORANGE, NEW JERSEY, ASSIGNOR TO WESTERN ELECTRIC COMPANY, INCORPORATED, OF NEW YORK, N. Y., A CORPORATION OF NEW YORK.

SWITCHING DEVICE.

1,271,124.

Specification of Letters Patent.

Patented July 2, 1918.

Application filed December 30, 1916. Serial No. 139,805.

To all whom it may concern:

Be it known that I, WILLIAM T. BOOTH, a citizen of the United States, residing at East Orange, in the county of Essex and 5 State of New Jersey, have invented certain new and useful Improvements in Switching Devices, of which the following is a full, clear, concise, and exact description.

This invention relates to a hook switch 10 especially adapted for use in subscribers' sets and its object is to provide a simple and compact device which will be efficient in operation, cheap to manufacture, and which may be used indiscriminately in different 15 types of sets.

There are two general types of so-called "wall sets" in common use at a subscriber's station, a non-flush type which is adapted for mounting directly on the wall, and a 20 flush type which is arranged to be set into the wall with which the front of the set is practically flush. In the former type it is the usual practice to have the lever of the hook switch project through a perforation 25 in the side wall of the set, while in the latter it is necessary that this lever project through the front of the set. In case the hook switch is arranged for mounting directly to the side wall or front of the set, it may be possible 30 to use the same hook switch in either type of set, but in many subscribers' sets, particularly those adapted for intercommunicating service, it often becomes desirable to assemble various parts of the apparatus, 35 including the hook switch, upon a mounting plate, which is later mounted within the subscriber's set casing. With this construction and the present type of hook switches it becomes necessary to supply hook switches 40 of different design for the different sets, making impossible the interchangeability of assembled units and thereby making it necessary to carry a greater variety of parts in stock.

45 In order to overcome the necessity for providing separate hook switches for flush and non-flush type sets this invention provides a hook switch of such a construction that it may be used equally satisfactorily with 50 either type.

This invention may be more clearly understood by reference to the accompanying drawings, in which Figure 1 is a front elevation of the containing case of a subscriber's 55 telephone set of a non-flush type, equipped

with a hook switch embodying this invention and arranged in this instance so that the lever projects through the side of the case; Fig. 2 is an enlarged view showing a section of the apparatus mounting plate with 60 a hook switch mounted for use in a non-flush set so that the lever extends through the side of the set as in Fig. 1; Fig. 3 is a front elevation of the containing case of a subscriber's set of the flush type equipped 65 with a hook switch in accordance with this invention; and Fig. 4 shows a section of the apparatus mounting plate with the hook switch mounted for use in a flush type set in such a way that the lever projects through 70 the front of the case.

The same reference figures are used to designate the same parts wherever shown.

The switch lever 4, having an operating end 5 and a hook end 6 adapted to hold the 75 receiver, is pivotally mounted to the bracket 7 by means of the pivot screw 8 and the shouldered bushing 9. Upon a bent-up extension 10 of the bracket 7 are mounted the customary springs 11, which are separated 80 from each other by means of insulating separators 12, and are held to the bracket by means of the screws 13. The extended portion 5 of the switch lever 4 bears against an insulating strip 14 of fiber or similar 85 material, fastened to the middle spring, and operates the contacts in the well-known manner. The body of the bracket is provided at either end with threaded mounting holes 15-15, and similar threaded holes 16-16 are 90 provided in the lugs 17 bent up at right angles to the body of the bracket. The distance between the holes 15-15 is the same as between the holes 16-16 and is equal to the distance between corresponding holes in the apparatus mounting plate 18. The hook switch is mounted to the apparatus mounting plate by means of mounting screws 19, the threaded portions of which pass through clearance 95 holes in the apparatus mounting plate, and engage the threaded holes 15-15 or 16-16, depending upon whether it is desired to use the unit with a non-flush or a flush type set. In Fig. 2 the mounting screws are shown engaging holes 15-15, this arrangement being 100 the one provided for a non-flush type set in which the hook lever projects through the side of the set. In Fig. 3 the mounting screws are shown engaging the holes 16-16, giving the arrangement desired for a flush 110

type set in which the hook lever projects through the front of the set. In the latter position the hook switch is rotated ninety degrees from its former position, clearance 5 for the lever being provided by the recessed portions 20 of the apparatus mounting plate.

Although a hook switch of this construction is particularly desirable for use in connection with a mounting plate, as shown, it 10 is not limited to use with a detachable mounting plate, but is equally desirable in those cases where the hook switch is to be mounted directly on the casing of the set.

What is claimed is:

- 15 1. In a switching device, a mounting plate, a bracket having a flat main portion and a plurality of angular extensions thereto, a plurality of circuit controlling members mounted on one of said extensions, an actuating member mounted on said main portion and in operative relation to said circuit controlling members, means on said main portion for mounting the device in a position whereby the actuating member is in a plane
- 20

parallel with the plane of said mounting 25 plate, and corresponding means on one of said angular extensions for mounting the device in a position whereby the actuating member is in a plane perpendicular to the plane of said mounting plate. 30

2. In a switching device, a mounting plate, a bracket comprising a flat main portion and a plurality of angular extensions, a plurality of contact springs mounted upon one of the angular extensions, an actuating member 35 pivotally mounted upon the main portion of the bracket in operative relation to the free ends of the contact springs, and means corresponding with openings provided in the main portion and the other angular extensions for mounting the bracket on the mounting plate with the actuating arm in a plane parallel with or at an angle to the plane of the mounting plate. 40

In witness whereof, I hereunto subscribe 45 my name this 29th day of December A. D., 1916.

WILLIAM T. BOOTH.
